UNITED STATES PATENT OFFICE.

CHRISTOPHER F. BARAGER, OF HONESDALE, PENNSYLVANIA.

JAR-LIFTER.

1,270,685.

Specification of Letters Patent. Patented June 25, 1918.

Application filed September 29, 1917. Serial No. 194,007.

To all whom it may concern:

Be it known that I, CHRISTOPHER F. BARAGER, a citizen of the United States, residing at Honesdale, in the county of Wayne and State of Pennsylvania, have invented new and useful Improvements in Jar-Lifters, of which the following is a specification.

This invention relates to jar lifters and 10 aims to provide a device which is especially adapted for lifting jars from hot water.

An object of the invention is to provide a device of this character in the form of a pair of tongs, each jaw of which is formed 15 from a single length of wire and bent to provide parallel lifting and retaining standards, one of said jaws carrying at one extremity a supporting platform, while the other jaw terminates short of this platform 20 to define a pusher element, by means of which the jar is pushed upon the platform, the opposite extremities of the standards being crossed and pivoted at such point of crossing and provided with hand grips.

25 The invention further includes connecting strips engageable with each pair of standards to prevent them from spreading.

In the drawings,

Figure 1 is a perspective view of the jar 30 lifting device embodying the present invention;

Fig. 2 is a vertical sectional view thereof on the line 2—2 of Fig. 1;

Fig. 3 is a transverse sectional view on 35 the line 3—3 of Fig. 1; and

Fig. 4 is a similar view on the line 4—4 of Fig. 1.

Referring to the drawings in detail wherein like characters of reference denote cor-

40 responding parts, the invention comprises a pair of tongs which includes a pair of jaws 10 and 11. The jaw 10 is formed of a single length of wire and is bent centrally to provide a loop, which includes a bearing 11' for the hand grip 12. The extremities of the bearing 11' provide parallel arms 13, which are bent at an angle as shown at 14 and are further bent to form parallel lifting and retaining standards 15. The extremities 45 of these standards are bent inwardly at an angle as shown at 16 and have secured thereon a supporting platform 17. The platform 17 has each of its ends curved around the extremity 16 which extends a short distance 50 therein, the curved portion 18 of the plat-

form being flattened as at 19 in order that it may be more readily slid beneath the bottom of a jar.

The opposite jaw 11 is bent centrally to provide a transverse portion 20 and parallel 60 standards 21, the opposite extremities of these standards being bent at an angle as shown at 22 and further bent to provide parallel arms 23, similar to the arms 13. The extremities of the arms 23 are bent inwardly 65 as shown at 24 to provide a bearing for the hand grip 25 similar to the grip 12. At the point of crossing of the angular portions 14 and 22, there is provided loops 26 and 27 respectively, which are adapted to 70 receive a pivoting bar 28 which extends across the tongs and has its extremities bent as shown at 29 to prevent accidental displacement.

Each of the jaws 10 and 11 and their respective parallel arms are connected by means of a strip 30 and 31 respectively which prevents the spreading of these arms. This strip is curved as shown to conform to the curvature of the jars and is secured to 80 the standards 15 and 21 by being bent around the same as shown at 32 and 33.

In the use of the device, the tongs are placed over the jar, the platform 17 being positioned adjacent the bottom of the said 85 jar. The hand grips 12 and 25 are then brought together, the pusher element serving to push the jar upon the platform 17, while the standards 15 and 21 hold the jar in position upon the said platform. The jar 90 may then be readily lifted without bringing the hands in contact with same or without the liability of the jar slipping from the platform 17.

Having described the invention, what is 95 claimed is:

1. A jar lifter embodying a pair of tongs, each of said tongs including a pair of parallel standards, oppositely located curved connecting strips positioned intermediate 100 the ends of each pair of standards, a laterally and inwardly extending platform located at the extremity of one jaw of said tongs to provide a jar support and the other jaw terminating short of the platform to 105 define a pusher element.

2. A jar lifter embodying a pair of tongs, one of which is formed from a single length of wire bent centrally to provide an outwardly curved connecting bar, parallel 110

standards rising from said connecting bar, offset parallel handle bars and inwardly curved extremities engageable with a grip or handle, the other tong being also formed of a single length of wire and bent centrally to provide a grip or handle receiving portion, offset parallel standards and inwardly

extending parallel terminals disposed below the connecting bar of the first mentioned tong, means for pivotally connecting the 10 tongs together and strips connecting each pair of parallel standards.

In testimony whereof I affix my signature.
CHRISTOPHER F. BARAGER.
